UNITED STATES PATENT OFFICE

HENRY A. OWEN, OF FOXBORO, MASSACHUSETTS, ASSIGNOR TO DAVIS & FURBER MACHINE COMPANY, OF NORTH ANDOVER, MASSACHUSETTS, A CORPORATION OF MASSACHUSETTS

GENERAL DRIVE FOR SPINNING FRAMES

Application filed April 10, 1930. Serial No. 443,014.

This invention relates generally to spinning frames and particularly to means employed to drive the various mechanisms incorporated therein, and has for its general object to provide a drive in which the power is distributed to the various yarn producing mechanisms by independent driving means the speed ratio of any one or more of which may be changed independently of the others.

10 A particular object of the invention is to provide a driving system in which the speed of the various driven elements may be changed with a minimum of effort and in the least possible period of time.

15 A further object of the invention is to provide a driving system in which power is distributed to the various driven elements from a common or a jack shaft incorporated in the machine.

20 The object of the invention is further to provide a driving system in which the means employed to change the production speed and the character of the yarn are efficient and flexible, and at the same time establish a positive speed ratio between the source of power 25 and the driven element.

A further object of the invention is to provide means whereby the production speed may be maintained constant while the factors regulating the character of the yarn are 30 changed.

A further object of the invention is to provide a driving system in which all of the elements are concentrated at one end of the machine and in which all adjustments can be 35 made from that end.

A further object of the invention is to provide a drive in which the direction of twist may be reversed without affecting the other 40 functions of the machine or requiring additional mechanism to prevent a change of direction in the other elements thereof.

A portion of the driving end of the spinning frame is illustrated embodying the elements constituting the invention and enough of the associated elements to present the principles of the invention. Inasmuch as the invention may be adapted to all types of spinning frames, the general structure of which 45 are well known to those skilled in the art, it

is deemed unnecessary to describe and illustrate a complete spinning frame.

In the drawings:

Fig. 1 is a plan view of the driving end of a spinning frame embodying the invention 55 in which parts of the end casing are broken away.

Fig. 2 is an end elevation of the parts shown in Fig. 1.

It is very desirable and from the standpoint of efficient production it is necessary that a spinning frame be constructed in a manner to be capable of producing a wide variety of weights and types of yarn. The present invention provides the maximum flexibility of adjustment combined with a positive distribution of power to the various elements. As a result of such construction the frame may be quickly and easily adapted to produce any desirable character of yarn. A common or jack shaft is embodied in the machine and driven at a constant speed either from a line of shafting, an individual motor or any suitable source of power. Individual drives are provided connecting the jack shaft 70 with each of the yarn producing mechanisms, namely, the spindles, the draft mechanism, and in wool spinning frames, the twister tubes. Each of the drives is adjustable to rotate its particular mechanism at a given 75 speed without affecting the speed of any of the remaining moving parts. In this manner a high degree of flexibility of adjustment is obtained.

In the specific embodiment illustrated the driving mechanism is mounted in a frame or casing 1 at the driving end of the machine. By concentrating the driving elements at one end of the machine all changes, replacements and adjustments therein are accomplished 80 from a single point thus reducing the labor and time required to change the character of the yarn produced by the machine. An electric motor 2 is employed herein to operate the machine. Any suitable source of power may however be employed. Mounted in suitable bearings 3 in the casing is a common driving or jack shaft 4 which may be connected to the motor 2 in any suitable manner. A desirable method is by means of a chain 5 running upon 85 90 95 100

a sprocket 6 on the motor shaft and a sprocket 7 upon the jack shaft 4.

The spindles 8 are driven from the usual drum 9 in any manner as by means of the usual driving bands. The driving end of the drum 9 which is herein shown is provided with a supporting shaft 10 journalled in a bearing 11 on the frame 1. Fixed to the end of the shaft 10 is a sprocket 12 over which extends a chain 13. The chain 13 functions to drive the drum and is itself driven by a sprocket 14 which is one of a plurality of sprockets of different diameters on the jack shaft, any one of which may be substituted for the sprocket 14. The group of sprockets on the jack shaft may or may not be integral with the sprocket 14. As illustrating a desirable structure the two other sprockets 15 and 16 are shown as integral and in axial alignment with the sprocket 14. The group of sprockets thus formed are preferably splined on the shaft 4 or fixed thereto in a manner to maintain a driving engagement and permit relative axial motion therewith. The speed ratio between the jack shaft and the drum may be changed by shifting the sprocket 15 or the sprocket 16 into the driving plane which the sprocket 14 occupies in the drawings. After selecting the proper sprocket the group is secured in place upon the jack shaft 4 by means of a set screw 17 or other suitable locking device. The sprockets may be separate instead of connected in a group as shown. In such case a locking device must be provided for each sprocket. Furthermore, it is not essential in either case that the sprockets be splined on the jack shaft since the locking device may act to transmit the power as well as retain the sprocket in the driving plane.

The distance between centers of the shaft 10 which drives the drum 9 and the jack shaft remains fixed. There must be provided therefore some means to take up the slack in the chain when the small sprocket sizes are functioning to drive the drum. To accomplish this an idler sprocket 18 is provided which is mounted on a support 19 movable in a slot 20 in the frame 1. The idler sprocket is positioned in a plane to engage the chain and is adjusted to take up slack therein by moving the support 19 along the slot 20 and is held in position by securing the support to the frame.

The particular type of frame herein illustrated is especially adapted to wool spinning and employs a series of twister tubes 21 associated with each spindle which function to induce a false twist in the roving during the drawing operation. The twister tubes 21 are driven from a drum 22 by means of the usual driving bands. Only the driven end of the drum 22 is shown, the other end thereof being suitably journalled in the end frame. A supporting shaft 23 is journalled in the casing

1 and has fixed to the end thereof a sprocket 24 which is driven by a chain 25 which in turn is driven by the jack shaft through a sprocket 26 which is one of a group of sprockets similar to the group of sprockets 14, 15 and 16. Only one additional sprocket 27 is however shown in this group. Several sprockets may be employed, however, which may be interchanged to secure the desired speed ratio between the jack shaft and the drum 22. The sprockets 26 and 27 are integral and have driving engagement with the shaft. Such engagement may be conveniently secured by splining the sprockets on a continuation of the spline upon which the other group of sprockets are mounted. The sprockets 26 and 27 are secured in the driving plane by means of a set screw 28.

When changing from the larger sprocket 27 to the small sprocket 26 the slack in the chain is taken up by means of an idler sprocket 29 mounted on a support 30 movable in a slot 31 in the casing. When the proper tension has been established in the chain by moving the sprocket 29 into engagement therewith the support is secured in place by means of a nut 32 which engages the casing.

A further feature of the invention consists in providing a reversing device by means of which the drum 9 may be reversed to establish a reverse twist in the yarn without disturbing the direction of rotation of any of the other elements. Upon the shaft 10 is secured a gear 33 which is constantly enmeshed with a gear 34 mounted on a short shaft 35 rotatably mounted in a bearing 36 fixed in the frame 1. To change the direction of rotation the sprocket 12 with the driving chain is removed from the shaft 10 and is made fast to the shaft 35. After such change the slack in the driving chain 13 is taken up by moving the idler sprocket 18 into position to maintain the required tension therein. After such change has been made the gear 33 then rotates the shaft 35 which rotates the gear 34 secured to it which in turn rotates the gear 33 to drive the drum 9 in a reverse direction.

The left hand draft roll is driven by a gear 37 mounted thereon which is one element in a train of gears leading to a gear 38 on the jack shaft. Interposed in this train of gearing is a gear 39 which is interchangeable with gears of various pitch diameters and meshes with the gear 37 acting to drive the draft roll. By substituting gears of different sizes for the gear 39 different speed ratios are obtained between the jack shaft and the draft roll to secure the desired production speed. To properly mesh the various sizes of interchangeable gears they are mounted on a shaft 40 which may be moved in a slot 41 in the frame 1 which is concentric with the axis of an intermediate shaft 120

42 having thereon a gear 43 which in turn meshes with a gear 44. The gear 44 is mounted on the shaft 40 and to it are secured the interchangeable gears. Obviously 5 the gears 43 and 44 will remain in mesh at all times while the shaft 40 is moved to bring the various interchangeable gears into mesh with the gear 37.

The right hand draft roll is driven in the 10 usual manner by means of a transverse shaft 45 suitably mounted on the frame 1. On the left hand draft roll is mounted a bevel gear 46 meshing with and driving a similar gear 47 on the transverse shaft 45 at the 15 other end of which is secured a bevel gear 48 meshing with a gear 49 on the right hand draft roll by means of which the latter is driven.

A suitable drive may be connected at some 20 point in the draft roll driving system to drive the builder motion cam 50. Such a drive is indicated generally at 51 and is connected to the right hand draft roll.

From the foregoing description it is obvious 25 that each of the functions involved in the spinning process may be modified to any desired extent without affecting the remaining functions. Moreover such changes may be very quickly and easily made. If the 30 speed ratios existing between the jack shaft and the various driven elements were to be changed in the usual way by removing the sprockets or other driving elements from the jack shaft and substituting others therefor, a great deal of useless time and labor 35 would be expended. Such waste of time and energy is entirely eliminated in the present device.

Having thus described the invention, what 40 is claimed as new, and desired to be secured by Letters Patent, is:

1. In a spinning frame, a jack shaft driven at a constant speed, independent mechanisms acting respectively to produce false twist and to produce the final twist in the roving, an independent drive from the jack shaft to each of said mechanisms, and means on the jack shaft operable to change the speed ratio of one of said drives independently of the other.

2. In a spinning frame, a jack shaft driven at a constant speed, independent mechanisms acting respectively to produce false twist and to produce the final twist in the roving, an independent drive from the jack shaft to each of said drives, and means on the jack shaft operable to change the speed ratio of either of said drives independently of the other.

3. In a spinning frame, a jack shaft driven at a constant speed, independent mechanisms acting respectively to produce a false twist and to produce the final twist in the roving, an independent drive from the jack shaft to each of said mechanisms, means on the jack

shaft operable to change the speed ratio of either of said drives independently of the other, a draft mechanism, and independent means acting to drive the same from said jack shaft and having interchangeable speed 70 determining elements to change the speed ratio thereof.

4. In a spinning frame, a jack shaft driven at constant speed, independent mechanisms acting respectively to produce false twist, to 75 produce a final twist and to draw the roving as it is spun, an independent drive from the jack shaft to each of said mechanisms having interchangeable speed determining elements on the jack shaft whereby the speed of any 80 of the mechanisms may be changed without affecting the remainder.

5. In a spinning frame, a jack shaft driven at constant speed, independent mechanisms acting respectively to produce the final twist 85 in the roving and to produce false twist therein, a driving element on each mechanism, a plurality of driving elements of different sizes slidable axially of said jack shaft and operable selectively to cooperate with the driving elements on said mechanisms to drive each mechanism at a predetermined speed independently of the remaining mechanisms.

6. In a spinning frame, the elements defined in claim 5 together with a draft mechanism and independent means acting to drive the same having interchangeable speed determining elements to vary the speed ratio thereof.

7. In a spinning frame, a jack shaft driven 100 at constant speed, independent mechanisms acting respectively to produce false twist and to produce the final twist in the roving, independent chain drives connecting the jack shaft with each mechanism, and means on 105 the jack shaft operable to change the speed ratio of one drive independently of the other.

8. In a spinning frame having the elements defined in claim 7 together with a draft mechanism and independent means acting to drive 110 the same having interchangeable speed determining elements to vary the speed ratio thereof.

9. In a spinning frame, a jack shaft driven 115 at constant speed, independent mechanisms acting respectively to produce false twist in the roving and to produce the final twist therein, a sprocket on each of said mechanisms, a chain passing over each sprocket, a plurality of sprockets of different diameters 120 mounted on and slidable axially of said jack shaft operable selectively to cooperate with the sprockets on said mechanisms and said chains to drive each mechanism at a predetermined speed independently of the other 125 mechanism, a draft mechanism, and driving means having interchangeable speed determining elements acting to drive the same from said jack shaft.

10. In a spinning frame, a jack shaft driven 130

at constant speed, independent mechanisms acting respectively to produce a false twist and to produce the final twist in the roving, an independent drive for each mechanism, 5 means on the jack shaft operable to change the speed ratio of either drive independently of the other, a draft mechanism, independent means acting to drive the same from said jack shaft having interchangeable speed determining elements to change the speed ratio thereof and means operable to effect a reverse twist in the yarn without modifying the movement of the other driven elements.

11. In a spinning frame, a drive supporting 15 frame at one end thereof, a jack shaft in the supporting frame driven at a constant speed, independent mechanisms acting respectively to produce false twist in the roving, to produce the final twist in the roving, independent 20 shafts for driving each of said mechanisms extending into the supporting frame, and means in the supporting frame for independently driving each of said shafts from the jack shaft and means on the jack shaft operable to change the speed ratio of each drive 25 independently of the others.

12. In a spinning frame, a drive supporting frame at one end thereof, a jack shaft in the supporting frame driven at a constant 25 speed, independent mechanisms acting respectively to produce the final twist in the roving and to draw the roving as it is spun, independent shafts for driving each of said mechanisms extending into the supporting 35 frame, means for driving each of said shafts independently from the jack shaft, the means for driving the shaft which drives the mechanisms producing the final twist being operable to effect a reverse twist in the yarn and 40 means on the jack shaft operable to change the speed ratio of the drive producing the final twist.

13. In a spinning frame, a jack shaft driven at constant speed, independent mechanisms 45 acting respectively to produce the final twist in the roving and to produce false twist therein, a driving element on each mechanism, a separate group of driving elements of different sizes to co-operate with the driving 50 element on each mechanism slidably axially of the jack shaft and operable selectively to change the speed ratio of the drive to each mechanism independently of the other.

In testimony whereof, I have signed my 55 name to this specification.

HENRY A. OWEN.

CERTIFICATE OF CORRECTION.

Patent No. 1,796,391.

Granted March 17, 1931, to

HENRY A. OWEN.

It is hereby certified that error appears in the printed specification of the above numbered patent requiring correction as follows: Page 3, line 56, claim 2, for "drives" read mechanisms; and that the said Letters Patent should be read with this correction therein that the same may conform to the record of the case in the Patent Office.

Signed and sealed this 14th day of April, A. D. 1931.
